UNITED STATES PATENT OFFICE.

JOSEPH McGRATH, OF MANTENO, ILLINOIS.

MAIL-TRANSFERRING APPARATUS.

1,192,656.

Specification of Letters Patent. Patented July 25, 1916.

Application filed September 14, 1915. Serial No. 50,682.

To all whom it may concern:

Be it known that I, JOSEPH McGRATH, citizen of the United States, residing at Manteno, in the county of Kankakee and State of Illinois, have invented certain new and useful Improvements in a Mail-Transferring Apparatus, of which the following is a specification.

My invention relates to mail transferring apparatus and contemplates primarily a novel delivery means for use in connection with a particular type of receiving apparatus hereinafter described.

The invention may be said to consist in the construction, combination and arrangement of parts hereinafter described and more particularly pointed out in the claims.

In the drawings, annexed: Figure 1 is a side elevation of my improved mail transferring apparatus; Fig. 2 is a longitudinal sectional view on the line 2—2 of Fig. 1; and Fig. 3 is a detail sectional view on the line 3—3 of Fig. 2.

Like numerals of reference designate like or corresponding parts throughout the several views.

Referring now to the drawings by numerals, 1 designates a railway mail car, 2 as an entirety the delivery means mounted thereon, 3 as an entirety the receiving means for co-operation with said delivery means, 4 as an entirety the delivery means for co-operation with the said means 2, the latter co-operating in this instance as a receiving means and 5 an opening or doorway in the mail car 1 that the delivery means 2 may be moved into and out of a position for operation.

For a brief description of the delivery means 2, attention is directed to a copending application bearing Serial #50,681, filed September 14th, 1915.

The receiving means 3 is conjunctively utilized as a means to receive and retain mail matter directed thereto through the agency of the delivery means 2 and as a means to guide and direct said means 2 (the latter in this instance being utilized as a receiving means) to the delivery means 4 mounted on said receiving means 3.

The delivery means 4 in its preferred embodiment may be said to consist of a suitable substantially rectangular frame 6 braced intermediate its ends as indicated at 7. Guide plates 8 diverge from the center of the frame toward the ends thereof that mail matter directed to the receiving means

3 may be held and retained as pointed out in the application above referred to and that the receiving means for the mail matter delivered may be directed to the delivery means 4. Divergent plates 8 terminate at their diverged extremities in spaced relation that the combined delivery and receiving means 2 may pass therebetween. Angle bars 9 (one for each plate) extend transversely of the frame and form a part thereof. Said angle bars 9 with a channel bar 10 secured thereto, afford a support means for holding devices designated, each as an entirety by the numeral 10'. The mentioned holding devices being of a duplicate construction, a description of but one will ensue.

A plate 11 is secured to the channel bar 10 to extend beyond the opposite longitudinal edges thereof as illustrated to advantage in Fig. 3. The terminals of the plate 11 act as the stationary jaws of the retaining device. A resilient plate 12 is secured at a point equi-distant from its ends or as indicated at 13 to the plate 11, said plate 12 being bowed at its extremities as indicated at 14 to provide the movable jaws of the retaining device. A pin 15 is mounted to penetrate the respective jaws of the holding device and to mount a spring 16 abutting at one end its associate movable jaw and at its opposite end a head 17 formed on the pin. The springs 16 afford a means whereby the resilient or movable jaws are normally held in engagement with the fixed or stationary jaws. As hereinbefore suggested, the retaining devices are located in opposed relation, that is, one set of jaws at each side of a line drawn through the center of the combined receiving and delivery frame. The said opposed retaining devices act together in releasably holding a mail bag support designated as an entirety by the numeral 18, said support comprising a metallic strip bent as illustrated to advantage in Fig. 3 to provide divergent arms 19 and a connecting loop portion 20, the former, arms 19, being provided with apertures 21 that the movable jaws 14 of the retaining devices may pass therethrough. A keeper 22 is pivoted as at 23 to one of the arms 19 in such proximity to the other of said arms as to normally engage therewith to thus provide a fastening means for the mail bag subsequent to engagement of the receiving means 2 therewith. The mail bag to be delivered, illustrated by the dotted line in Fig.

1, is detachably connected in any suitable manner to a lug 24 formed upon one of the divergent arms. That the said arms 19 may contact with the retaining devices as hereinbefore suggested, the openings 25 are formed in the guide plates 8 in opposed relation. As indicated in Fig. 3, and even better in Fig. 1, the retaining devices are so positioned relatively to the guide plates 8 as 10 to coact with the receiving means directed thereto from either side or rather end of the frame 6.

In operation, the mail bag to be transferred is fastened to the delivery means 4 15 by any suitable means. Movable jaws 14 of the retaining devices are next removed from engagement with the stationary jaws 11 of the said devices against tension of the springs 16. When so removed, the arms 19 20 are positioned in such relation to such devices as to allow the movable jaws, when released, to fit the openings 21 in said arms and by such fitting engagement hold the delivery means 4 in the direct path of the receiving means 2 directed thereto by contact 25 with the guide plates 8. The arms 19 of the delivery means of course penetrate the guide plates 8 at the opposite end of the frame 6 from that whence a mail train is approaching. As the receiving arms come in contact 30 with the diverged plates 8 it is evident that the said arms will be directed against the keeper or latch bars 22 and to the loop portion 20 of the delivery means. The impact 35 occasioned by the contact of the receiving means with said delivery means will be sufficient to withdraw the arms 19 from engagement with the retaining devices and thus cause said delivery means 4 or rather the plates 18 forming a part thereof together 40 with the mail bag to be transferred from the stationary support to the moving train.

It will be understood that the above description and accompanying drawings comprehend only the general and preferred embodiment of my invention and that various minor changes in details of construction, proportion and arrangement of parts may be made within the scope of the appended 50 claims and without sacrificing any of the advantages of my invention.

Having thus fully described my invention, what I claim as new and desire to secure by Letters Patent, is:—

1. In a mail delivery apparatus, a removable support for the mail bag to be delivered, a retaining means engaging and holding said support in a position for delivery, said support accompanying the bag when delivered, and a guide means leading 60 to said support.

2. In a mail delivery apparatus, a removable support for the mail bag to be delivered, spring actuating jaws engaging and holding said support in a position for delivery, said support accompanying the bag 65 when delivered, and a guide means leading to said support.

3. In a mail delivery apparatus, a support for the mail bag to be delivered comprising a single strip of material bent to provide a looped retaining portion and arms leading therefrom, spring actuated clamping jaws engaging the respective arms to maintain the support in a position for delivery, guide plates leading to said support, 70 each of the mentioned guide plates having openings formed therein through which the arms of the said support extend, substantially as described.

4. In a mail delivery apparatus, a mail bag support comprising a looped retaining member having divergent arms leading thereto, each of said arms having an opening formed therein, opposed retaining devices adapted to engage the respective arms, each of said devices comprising a fixed jaw and a spring actuated movable jaw adapted for contact therewith, the said movable jaws fitting openings aforesaid, and guide plates 85 leading to said support means, the mentioned guide plates extending in divergent relation and being provided with openings through which the said arms pass, substantially as described.

In testimony whereof I affix my signature in presence of two witnesses.

JOSEPH McGRATH.
